BURIAL VAULT

Filed April 15, 1929

INVENTOR:
DANIEL E. JONES.

By James L. Hopkins
Attorney.

UNITED STATES PATENT OFFICE

DANIEL E. JONES, OF ST. LOUIS, MISSOURI, ASSIGNOR TO CLIFFORD L. FLAVEN, AS
TRUSTEE

BURIAL VAULT

Application filed April 15, 1929. Serial No. 355,401.

My invention relates to improvements in burial vaults and has for its object to provide a double walled vault of unitary construction adapted to the preservation of the casket held within the inner compartment, and the maintenance of dryness in the casket receptacle by means of the air spaces between said casket receptacle and the outer receptacle or sarcophagus.

10 The vault of my invention is adapted to be constructed in a factory and of a bulk readily transportable, or may be of dimensions and weight necessitating its construction in situ. It is equally adapted for the interment of the entire structure or for use above ground as a mausoleum. It may be formed of metal or cementitious material as desired.

In the drawings:

Figure 1 is a vertical longitudinal view in mid-section of a structure embodying my invention.

Figure 2 is a top plan view of the same, partly in section on the line 2—2 of Figure 1.

Figure 3 is an end view of the same, partly in section on the line 3—3 of Figure 2.

25 The sarcophagus "A" encloses the casket receptacle "B" and is integrally formed with the vertical walls 5 thereof by means of the buttresses 4, as shown, the vertical walls 5 having the inturned flange 6 formed at their 30 inturned lower edges to receive the bottom 6 of the casket receptacle "B".

The sarcophagus "A" has the lid or cover 7 with the depending flange 8 fitting the mouth of the sarcophagus "A". The lid or cover 7 is of larger area than the mouth of the sarcophagus "A" and is preferably provided with the groove 9 beneath its projecting margins to prevent the passage of water to the mouth of the sarcophagus "A".

40 The casket receptacle "B" has a lid or cover 10 with the depending flange 11 enabling it to accurately fill the mouth of the casket receptacle "B".

45 There is thus provided an air chamber "C" entirely surrounding the casket receptacle "B" save where it is interrupted by the buttresses 4—and the buttresses 4 are so disposed as to permit the free vertical circulation of 50 air within the air chamber "C" due to varia-

tions in temperature within the air chamber "C", to the end of maintaining the casket receptacle "B" in as dry condition as possible, whether the vault be underground or mounted above ground.

55 I have indicated at 12 a boss formed on the upper face of the lid 7 for the reception of an inscription plate 13. Through the boss 12 a vertical vent 14 is provided to accommodate air resistance in seating the lid 7 in place; the lid 7 having been seated, the vent 14 is sealed by a plug 15 of any suitable material, whereupon the inscription plate 13 is mounted in place.

60 If preferred, the casket receptacle "B" may be of material other than that of the sarcophagus "A", and not be molded or cast integrally with the buttresses 4, and other structural variations may be effected without departure from my actual invention as defined 65 by the appended claim.

I claim:

A burial vault comprising an integral structure having spaced inner and outer walls and an outer bottom, said inner and outer walls being connected by buttresses, the bottom edges of said inner walls having inturned flanges, a separate bottom member for the chamber formed by the inner walls resting upon the inturned flanges, a removable lid for the chamber formed by the inner walls and flanges to engage said walls, and a removable lid for the chamber formed by the outer walls and flanged to engage the same.

75 In testimony whereof I have hereunto affixed my signature.

DANIEL E. JONES.
